UNITED STATES PATENT OFFICE.

LEONARD ZIEGLER, OF NUTLEY, NEW JERSEY.

SPARK INDICATOR.

Application filed December 21, 1921. Serial No. 523,909.

To all whom it may concern:

Be it known that I, LEONARD ZIEGLER, citizen of the United States, residing at Nutley, in the county of Essex and State of New Jersey, have invented certain new and useful Improvements in Spark Indicators, of which the following is a specification.

This invention relates to an improved spark indicator for internal combustion engines and seeks, as one of its principal objects, to provide a device particularly adapted for use in connection with motor vehicles and wherein the spark plugs of the engine of a vehicle may be tested while the vehicle is in motion.

A further object of the invention is to provide a device wherein the spark plugs of an engine may be tested under working conditions of the engine.

And the invention has as a still further object to provide a device which will be neat and attractive in appearance and may be readily installed upon motor vehicles of substantially any conventional design.

Other and incidental objects will appear hereinafter.

In the drawings:

Figure 1 is a perspective view of my improved indicator,

Figure 2 is a section on the line 2—2 of Figure 4, looking in the direction of the arrows,

Figure 3 is a section on the line 3—3 of Figure 2, looking in the direction of the arrows,

Figure 4 is a section on the line 4—4 of Figure 2, looking in the direction of the arrows,

Figure 5 is a rear elevation of the device, and

Figure 6 is a sectional view showing an improved spark plug employed in conjunction with the indicator.

Referring now more particularly to the drawings, it will be seen that I employ a cylindrical casing 10 having a forward end wall 11 and bent adjacent its outer end to provide a stop flange 12. Seated in the forward end of the casing to abut the end wall 11 is a front block 13 from which extends a centrally disposed annular flange 14 projecting from the front face of the block through the end wall of the casing. As particularly shown in Figure 1, the front block is secured to said end wall by fastening devices

15 and mounted in the casing at its inner end is a back block 16 secured in position by fastening devices 17. The front and back blocks 13 and 16 are of porcelain or other approved insulating material and fitting within the casing between said blocks is a spacing ring 18 which is also preferably of insulating material.

Mounted upon the front block 13 at its inner side is a metallic switch plate 19 provided, as best shown in Figure 3, with a semi-circular opening 20 and securing the switch plate is a bolt 21 extending forwardly through said block. The block carries a second bolt 22 projecting at its inner end through the opening 20 in the switch plate and mounted upon the outer ends of said bolts are electrodes 23 housed by the flange 14 and forming a spark gap therebetween. Rising from the switch plate at circumferentially spaced points thereon are pairs of coacting resilient switch fingers 24. The block 16 is provided with a central opening 25 therethrough and mounted upon said block at its inner side to surround said opening is a switch plate 26 secured to the block by bolts 27. Rising from the plate at circumferentially spaced points thereon are pairs of coacting switch fingers 28 similar to the fingers 24.

Extending through the block 16 is a circularly disposed series of bolts 28 and projecting through the block between said bolts is a similar series of squared sleeves 29 provided at their outer ends with plates 30 engaged by the bolts. Each of the bolts is thus electrically connected with one of the sleeves respectively. Slidable through the plates 13 and 16 are switch rods 31 which, at their inner end portions are squared to fit through the sleeves 29, the sleeves locking the rods against rotation, while at their outer ends, said rods are equipped with buttons 32. Extending from the rods are switch arms 33 each engageable between a pair of the switch fingers 28 respectively upon the plate 26 while, as shown in dotted lines in Figure 2, the rods may be pulled rearwardly to engage each of said arms between a corresponding pair of the switch fingers 24 respectively upon the plate 19. As will be observed, I have shown the use of six of the switch rods 31, the present device being designed for use in connection with a six cylinder engine. However, as will be at

once understood, the device may comprise a greater or lesser number of rods and associated parts to meet the requirements of different engines. In practice, the device 5 may be mounted upon the dash of a vehicle, as conventionally illustrated at 34, projecting through the dash so that the stop flange 12 of the casing 10 abuts the dash and extending through said flange are appropriate 10 fastening devices securing the indicator in position.

In conjunction with the indicator, I employ a spark plug of the character illustrated in Figure 6, the plug shown being 15 typical. As will be observed, the plug comprises a shell 35 threaded at its lower end for engagement in the usual spark plug orifice of an engine cylinder and extending through the shell is an insulator 36 of porcelain or other approved material. Surrounding the insulator are gaskets 37 and threaded into the upper end of the shell to coat with the uppermost of these gaskets is a nut 38 removably clamping the insulator 20 upon the shell. Extending through the insulator are electrodes 39 and 40 to the upper ends of which are connected binding posts 41 carried by an insulating cap 42 upon the upper end of the insulator. At its lower 25 end the electrode 39 is provided with a laterally directed portion while upon the lower end of the electrode 40 is formed a loop through which the laterally directed portion of the electrode 39 extends to provide a 30 spark gap between the electrodes.

As will now be understood, each of the cylinders of the vehicle engine is equipped with one of my improved plugs. Feed wires are then attached to the binding posts of the 40 electrodes 39 of the plugs when wires are then arranged to extend between the electrodes 40 of the plugs and the several bolts 28 of the indicator, these latter wires being indicated in Figure 2, at 43. Connected at 45 one end to the bolt 22 of the indicator is a wire 44 which is led through the opening 25 in the plate 16 to a suitable electrical ground and connecting one of the securing bolts 27 for the switch plate 26 with said 50 wire is a wire 45 so that said switch plate is also grounded. Normally, the several switch rods 31 will occupy the position shown in Figure 2, so that the switch arms 33 of said rods engage the switch fingers 28 for closing 55 a circuit for each of the spark plugs through one of the wires 43, one of the bolts 28 and one of the sleeves 29 to the ground wire 44. Thus, all of the plugs will normally be connected with the ground wire so that said 60 plugs may function. To test the plugs, the buttons 32 are grasped and the rods 31 drawn outwardly one at a time, to engage the switch arms 33 of said rods with the switch fingers 24. As each of the rods is 65 thus drawn outwardly, the circuit of one of

the plugs respectively will be closed through the plate 19 and electrodes 23 to the bolt 22 and thence to the ground wire 44. Accordingly, if the plugs are functioning properly, a spark will be given off at the gap between 70 said electrodes when each rod is drawn outwardly. On the other hand, should any one of the plugs be short circuited to the engine, no spark will appear at the gap between the electrodes 23 and accordingly, the faulty 75 plug may be easily located. As will be perceived, I provide a device wherein the plugs of the vehicle engine may be easily tested without stopping the vehicle and under working conditions of the engine. 80

Having thus described the invention, what is claimed as new is:

1. A spark indicator including spaced blocks, a switch plate carried by each of said blocks, coacting electrodes upon one of the blocks forming a spark gap in circuit with one of said plates, and a switch rod 85 slideable upon the blocks to selectively coat with the plates.

2. A spark indicator including spaced blocks, a switch plate carried by each of said blocks, a sleeve upon one of the blocks, and a switch rod slideable through said sleeve to selectively coat with said plates, the rod 90 being in circuit with the sleeve. 95

3. A spark indicator including spaced blocks, a switch plate carried by each of said blocks, a terminal upon one of the blocks, a sleeve secured by said terminal in circuit therewith, and a switch rod slideable 100 through the sleeve to selectively coat with said plates.

4. A spark indicator including spaced blocks, a switch plate carried by each of said blocks, a terminal upon one of the blocks, a sleeve extending through said block and provided at one end with a plate 105 engaged by said terminal securing the sleeve upon the block, the sleeve being in circuit with the terminal, and a switch rod slideable 110 through said sleeve to selectively coat with the switch plates.

5. A spark indicator including spaced blocks one provided at the front face thereof with a forwardly directed flange, coacting electrodes mounted upon said block to provide a spark gap therebetween and housed by said flange, switch plates upon the blocks at the inner faces thereof one said 115 plate being in circuit with said electrodes, 120 and a switch rod slideable through the blocks to selectively coat with said plates.

6. A spark indicator including a casing, spaced blocks removably fitting therein from one end of the casing, a spacer between the blocks, means connecting one of said blocks with the casing securing both blocks against displacement, and switch mechanism associated with said blocks. 125

7. A spark indicator including a casing 130

provided at one end with an annular end wall, spaced blocks mounted in the casing, one of said blocks abutting said end wall and being provided with an annular flange 5 projecting through the end wall, coaxing electrodes upon said blocks housed by said flange, switch plates upon the blocks one in circuit with said electrodes, and a switch rod slidable upon the blocks to selectively 10 coat with said plates.

provided at one end with an annular end wall, spaced blocks mounted in the casing closing the ends thereof, one of said blocks abutting said end wall, a spacer between the blocks, means connecting the other of said blocks with the casing securing both blocks against displacement, and switch mechanism associated 15 with the blocks.

20

In testimony whereof I affix my signature.
LEONARD ZIEGLER. [L. s.]

8. A spark indicator including a casing
